UNITED STATES PATENT OFFICE.

WALTER E. HUME, OF RUTHERFORD, NEW JERSEY.

SUPPORT FOR DRESS-FORMS AND THE LIKE.

1,101,552.

Specification of Letters Patent. Patented June 30, 1914.

Application filed July 3, 1913. Serial No. 777,176.

To all whom it may concern:

Be it known that I, WALTER E. HUME, of Rutherford, Bergen county, New Jersey, have invented a new and useful Improvement 5 in Supports for Dress-Forms and the like, of which the following is a full, clear, and exact description.

My invention relates to improvements in supports for dress forms or analogous structures, and the object of my invention is to produce a simple, inexpensive, and reliable form of support by which the dress form or other article supported, can be easily raised and lowered, and to provide in connection 10 with the same a positive lock which will automatically lock and hold the form at a desired height, which will permit its rotation, and which has a handle mechanism by which the form can be raised or lowered, the handle mechanism serving also to release the 15 automatic lock. Thus the operator can grasp the handle mechanism and without any other operation raise or lower the form as desired, and on releasing the handle 20 mechanism the apparatus will automatically lock itself.

In carrying out my invention I use a form of lock which is not broadly new, but which is novel, I think, in connection with the 25 handle mechanism which acts as above described.

Reference is to be had to the accompanying drawings forming a part of this specification, in which similar reference characters indicate corresponding parts in all 30 the views.

Figure 1 is a side elevation of the complete apparatus. Fig. 2 is a detail vertical section on an enlarged scale, of the handle 40 and locking mechanism. Fig. 3 is a plan view of the handle and locking mechanism with the supporting post removed. Fig. 4 is a detail side elevation of the housing in which the mechanism is located, and Fig. 45 5 is a cross section on the line 5—5 of Fig. 4.

The apparatus is provided with a suitable base 10 which as shown is mounted on casters, and which is of the customary kind, rising from which is a post 11. A tube 12 50 slides and turns on the post, and carries on its upper end a dress form 13 or other article which is desired to be supported. At the lower end of the tube 12 is a collar 14 which serves also as a cap for the housing, and 55 between which and the tube 12 is a washer 15. The collar has on one side a hand grip

16, which comes opposite the handle 23 hereinafter referred to. Immediately below the collar 14 and connected therewith so as to practically form a part thereof, is a housing 60 17, the inner wall of which on one side is inclined as shown at 18 in Fig. 2, and between this inclined wall and the post 11 is a rolling member which is preferably a ball 19, and which is normally pressed upward by a spring 20 arranged between the ball and the bottom of the housing, and supported on a screw 21. It will be seen that the way in which the ball runs is narrower 65 at the top than at the bottom, and consequently the weight of the form 13 and tube 12 will cause the rolling wedge member to be wedged between the inclined wall and the post 11, so as to automatically lock the tube 70 12 and hold it and the form or other matter 75 which it carries, at the height at which it happens to be when the handle mechanism is released, as hereinafter described.

The rolling member or ball 19 is placed immediately beneath the short end 22 of the 80 handle 23, which is pivoted as shown at 24 in the slot 25 in the upper part of the housing, and immediately above the inclined wall 18. The handle mechanism is located at the lower end of the tube 12 so as to be 85 arranged below the skirt or garment which may be supported on the form 13, this making it more convenient to use.

It will be seen that the form 13 can turn freely on the post 11, but when the form 90 or analogous article is to be adjusted vertically, the operator simply grasps the hand grip 16 and handle 23, which pushes down the inner end of the handle and depresses the ball 19 so that the tube 12 and article 95 which it carries, can at the same time be raised or lowered by the handles. When these are released, the ball immediately assumes its wedging position between the wall 18 and the post 11, and the device is 100 securely locked.

I am aware that there is nothing broadly new in using a rolling wedge and a fastening means, but by arranging it in combination with the handle mechanism and article 105 to be raised or lowered as described, it will be seen that I get not only a fastening means, but an automatic releasing and locking means, so that when the handles are grasped to raise or lower the device, the 110 lock is automatically released, while by releasing the handles, the locking device auto-

matically locks itself. The construction, it will be noted, is extremely simple and positive, there is nothing to get out of order about it, and it is so cheap in construction 5 that it is a great advantage in the class specified because these articles are necessarily cheap.

It will be observed that the housing 17 is separate from the tube 12, as the structure 10 can be more cheaply made this way and works better, but if the housing were simply an enlarged part of the tube 12, the operation would of course be the same.

I claim:

- 15 1. A structure of the class described, comprising a supporting post, a tube sliding thereon, a housing on the tube, said housing having an inclined wall, a spring pressed rolling wedge member between the 20 inclined wall and the post, a handle pivoted

in a slot in the housing and having its inner end contacting with the rolling wedge member, and a hand grip projecting from the housing parallel with the said handle.

2. A structure of the class described, comprising a supporting post, a tube sliding and turning on the post, a housing at the lower end of the tube, said housing having a slot in one end and an inclined wall below the slot, a spring pressed rolling wedge member between the inclined wall and the post, a handle pivoted in the aforesaid slot and having its inner end adapted to contact with the rolling wedge member, a cap for the housing, and a hand grip projecting from the cap opposite the said handle. 25 30 35
